UNITED STATES PATENT OFFICE

ARTHUR VON FRANKENBERG, OF NEW YORK, N. Y.

DESIGN FOR A COMBINED ASH TRAY AND RECEPTACLE SUPPORT OR SIMILAR ARTICLE

Application filed November 14, 1930. Serial No. 37,649. Term of patent 7 years.

To all whom it may concern:

Be it known that ARTHUR VON FRANKENBERG, citizen of the United States, and resident of New York city, in the county of New York and State of New York, has invented a new, original, and ornamental Design for a Combined Ash Tray and Receptacle Support or Similar Article, of which the following is a specification, reference being had to the accompanying drawing, forming part thereof, in which the figure is a perspective view of an ash tray embodying my new design.

I claim:

The ornamental design for a combined ash tray and receptacle support or similar article, substantially as shown.

Dated, November 11, 1930.

ARTHUR VON FRANKENBERG.
